COMBINED INHALATOR AND IRRADIATOR

Albert L. Miller, Los Angeles, Calif.

Application July 18, 1936, Serial No. 91,306

22 Claims. (Cl. 128—190)

My invention relates to a device using a source of ultra-violet rays for the combined utility of irradiation of parts of the human body and the ozonization of air to be breathed. The therapeutic value of high frequency rays, such as ultra-violet rays, and of products resulting from treatment of various substances with ultra-violet rays, is apparently now extensively recognized.

It is an object of the invention to provide a simple, inexpensive, and portable device in which one source of ultra-violet rays may be conveniently used for several therapeutic uses.

It is an object of the invention to provide a device having a source of ultra-violet rays, for example, a cold quartz tube, and means whereby this cold quartz tube may be employed to irradiate portions of the body or to irradiate a stream of air which is conducted through a closed passage and is discharged so that it may be breathed through the respiratory passages into the lungs. I have found that very great benefits are to be attained by this multiple use of treating human ailments. I take extensive advantage of the ability of ultra-violet rays to produce changes in substances which are subjected to irradiation. In the device I provide a means whereby a flow of air is conducted in close proximity to the cold quartz tube, with the result that a state or substance is produced in the air known scientifically as "ozone," which may be referred to as activated oxygen. This irradiated oxygen, when breathed into the lungs, produces effects which lead an observer to believe that it is immediately taken up by the blood stream and that the purifying and cell rebuilding capacity of the blood stream is thereby greatly enhanced. I have found that if, in conjunction with the breathing of irradiated air, or ozone, the external parts of the body are subjected to irradiation so that the skin structure and possibly the cells lying under the area of skin irradiated are given a content or characteristics conducive to normalizing of the body functions, valuable therapeutic results are attained.

The remarkable results obtained by this combination use of ultra-violet rays might lead to the building up of elaborate theories as to what takes place in the human body under treatment, but I expressly desire to avoid all elements of theory, if possible, and merely refer to some of the benefits obtained. The various ailments consisting of or resulting from toxic conditions, for example, headaches, may be very quickly relieved. The various ailments concerned with the respiratory tracts, principally asthma, bronchitis, sore throat, and head colds, are quickly benefited. The nor-

malizing effect on the functions of the human body is to be particularly noted.

It is an object of the invention to provide a device of the character set forth hereinabove having a holder for an ultra-violet ray emission means holding the ray emission means in such a manner that the rays therefrom may be employed to irradiate portions of the human body, and in conjunction with the foregoing a wall adapted to cooperate with the holder so as to form a closed space containing the ray emission means, and further to provide means for conducting a flow of air through this space in such a manner that it will pass in close proximity to the ray emission means. In the preferred practice of the invention the ray emission means includes a cold quartz tube bent to spiral form, and the tube is supported in the chamber in such a manner that practically all of the air to be treated will pass within a prescribed distance of the surface of the tube. I have found that very satisfactory ozonization of the air may be accomplished by bringing the air into a position not greater than four millimeters from the surface of the tube.

It is a further object of the invention to provide a device such as set forth in the preceding paragraph wherein the holder for the cold quartz tube is of small size and light weight so that it may be detached from the stationary wall which cooperates with it to form a chamber for ozonization of air, and to further provide a handle for such holder adapted to be gripped manually and held in a desired position relative to any part of the body to be irradiated. In this device the source of high potential electric current for operation of the cold quartz tube is preferably secured within the portable case carrying the hereinbefore referred to stationary wall and other mechanisms concerned with the operation of the device, as, for example, a blower for producing the flow of air to be ozonized, switches, meters, etc. The source of high potential current is preferably a transformer, and this transformer is connected through a flexible conductor to the manually transportable, light-weight holder for the cold quartz tube.

It is a further object of the invention to provide means for cooling or minimizing the temperature rise in the ozonized air, and further to provide simple means detachably secured to an air outlet provided in the holder, for holding a body of liquid, such as aromatic or healing oils, in such position that the ozonized air must pass therethrough to a discharge attachment from which the patient breathes the treated air. The

discharge attachment may be connected directly to the ozone outlet so that the irradiated air will be carried to the patient without passing through the liquid.

5 Further objects and advantages of the invention will be made evident throughout the following part of the specification.

Referring to the drawings, which are for illustrative purposes only,

10 Fig. 1 is a front view of a preferred form of the invention showing the parts thereof arranged for delivering ozonized air.

Fig. 2 is a cross section on a plane indicated by the line 2—2 of Fig. 1.

15 Fig. 3 is a face view similar to Fig. 1, but showing the irradiator element disconnected from the supporting wall of the cabinet so as to be used for the purpose of human body irradiation.

20 Fig. 4 is an electrical diagram of the device shown in the preceding figures.

Fig. 5 is a fragmentary section taken as indicated by the line 5—5 of Fig. 1.

Fig. 6 is a face view of the cold quartz tube holder.

25 Fig. 7 is a fragmentary section taken as indicated by the line 7—7 of Fig. 6.

Fig. 8 is an enlarged fragmentary section on the line 8—8 of Fig. 1.

30 Fig. 9 is a view showing a fragment of the wiring diagram wherein a change is made enabling the alternative practice of the invention.

As shown in Figs. 1 and 2, I provide a portable case 10 which may be provided with a handle 11. In the upper portion of the case 10 a substantially vertical supporting wall 12 is mounted. At the lower end of the supporting wall 12 there is a horizontal wall 13 below which there exists an opening 14 in which a drawer 15 may slide, this drawer 15 being of such size that electric 40 tension cords and reserve supplies of materials may be kept therein.

At one side of the wall 12, for example, the left side thereof, there is an opening 16 concentric with which a plate 17 may be mounted by 45 use of small bolts 18. This plate 17 has a rearwardly projecting annular wall 19 forming a fan or blower chamber 21 in which a rotary fan 22 is supported. A plate 23 is secured to the rightward or inner edge of the wall 19 to substantially 50 close the chamber 21, and in this plate 23 is an opening 24 through which a shaft 25 extends from a motor 26 into the chamber 21 so as to rotate the fan 22. This motor 26 is mounted on brackets 27 which may be secured to the plate 17. 55 The plate 23 has an inlet opening or port 28 for the fan chamber 21, and a swingable gate 29 may be provided for controlling the flow of air through the opening 28. The discharge for the rotary fan mechanism disclosed consists of a plurality 60 of relatively small openings 31 disposed substantially in a circle so as to connect the peripheral portion of the fan chamber 21 with the front face of the plate 17. As shown in Fig. 2, a circular wall 32 projects leftwardly or forwardly 65 from the plate 17 to serve as a means for centralizing a detachable holder 33 relative to the plate 17. This holder 33 includes a front wall 34 of dish-shaped form so as to provide a convex portion or dome 36, an annular cylindrical wall 37, an annular radial wall 38 at the rightward or inner edge of the wall 37, a cylindrical wall 39 projecting rearwardly from the periphery of the radial wall 38 and being of such internal diameter that it will fit closely around the annular wall 32, and a radial wall or flange 41 at

the inner edge of the cylindrical wall 39, this flange 41 being adapted to rest against a flange 42 extending peripherally around the plate 17. The holder 33 is detachably secured in position on the plate 17 as shown in Figs. 1 and 2 by use of 5 quickly attachable and detachable means constructed as follows.

As shown in the lower right-hand corner of Fig. 3, the flange 41 of the holder 33 has a plurality of circular openings 43 from which slots 10 44 extend in clockwise direction. Mounted on the flange 42 of the plate 17 are pins 45 having heads 46 of a size to pass through the openings 43. The inner faces or shoulders 47 of the heads 46 are spaced from the front face of the flange 15 42 a distance slightly greater than the thickness of the flange 41 so that when the holder 33 is placed upon the front of the plate 17 so that the heads 46 will pass through the openings 43 to permit the flange 41 to engage the flange 42, 20 rotation of the holder 33 in clockwise direction will cause the metal walls 48 lying on opposite sides of the slots 44 to pass under the shoulders 47 of the heads 46, thereby locking the flange 41 against the flange 42.

25 Against the intermediate radial wall 38 within the holder 33 a circular wall 50 is secured by means such as small screws 51. This wall cooperates with the annular wall 32 and the plate 17 to form a shallow irradiation or ozonization chamber 52. On the outer face 53 of the plate or wall 50 is secured an ultra-violet ray emanating means in the form of a cold quartz tube 54 which is substantially 4½ feet long and is bent to form a spiral as best shown in Fig. 3. This tube 54 is 30 preferably held in spaced relation to the plate 50 by use of small tie wires 55 which may be looped twice around the tube, as shown in Fig. 3, and then passed through openings 56 in the plate 50, whereupon the free ends thereof are twisted together as shown at 57. The outer end 58 of the tube 54 bends rearwardly and passes through an opening 59 in the wall 50, and the inner end 61 of the tube 54 bends rearwardly and extends through an opening 62 in the wall 50 which is 40 large enough to form an irradiated air or ozone outlet for the chamber.

45 A handle 63 is connected to one side of the wall 34 which forms the dome 36, and extends in a plane parallel to the supporting wall 12. 50 As shown in Fig. 1, the handle 63 is preferably so placed that it will project rightwardly from the holder 33 within the case 10 and across the front face of the wall 12. A flexible, insulated cable 64 extends through the handle 63 into the 55 interior space 65 of the dome 36, and the conductors 66 and 67 thereof are connected to the ends of the cold quartz tube 54, as shown in Fig. 2.

When the motor 26 is energized, the fan 22 60 through its centrifugal action produces an air pressure in the peripheral portion of the fan chamber 21, with the result that air is driven through the plurality of small openings 31 into the outer portion of the irradiation chamber 52. 65 This air then passes radially inwardly through the narrow spaces 68 formed on opposite sides of the tube 54, or, in other words, between the tube 54 and the wall 50 and the plate 17. These spaces 68 are preferably from $\frac{1}{2}$ to $\frac{1}{8}$ of an inch in width, 70 and therefore the air in passing from the inlet openings 31 of the chamber 52 to the outlet opening 62 must pass in close proximity to the surfaces of the tube 54, with the result that if the tube is energized, a very effective irradiation, 75

known as ozonization, of the air will take place. This irradiated or ozonized air passes into the interior space 65 of the dome 36, which space 65 forms a cooling chamber, and from this space 65 the ozonized air passes through an outlet tube 69 formed at the leftward side of the wall 34, then through a gooseneck fitting 71, a U-shaped glass tube 72, a fitting 73, and a hose 74 to a breather attachment 75 adapted to fit over the nose and mouth of a person. The side wall of the breather attachment has several small openings 76 therein through which the breath may be discharged. A quantity of liquid 77 is placed in the glass tube 72. This liquid is preferably a mixture of healing oils such as those recognized as having properties beneficial to inflamed conditions of the respiratory tract. The ozonized air bubbles through this liquid 77, and vapors from the liquid are entrained in the flow of air. The concentration of ozone produced by my device is such that a thirty minute period of breathing the same will be sufficient to accomplish results desired, but breathing the ozone for a greater period of time is in no way harmful and may be necessary for the treatment of aggravated cases. Where untreated ozone is desired, the fitting 73, which is tubular in character, may be removed from the end of the glass tube 72, and the fitting 71 may be removed from the outlet tube 69, the fitting 73 being then fitted onto the outlet tube 69 as indicated in dotted lines in Fig. 5. After the breathing of ozone or irradiated air from the device, as previously described, the tube holder 33 may be removed from its operative position on the supporting wall 12 shown in Figs. 1 and 2. The patient may then conveniently supplement this treatment with irradiation of the surface portions of the body. This may be done by removing the holder 33 and applying the ultra-violet emanations directly to the body. Removal of the holder 33 is accomplished by lifting upwardly on the handle 63, Fig. 1, so as to rotate the holder 33 in anti-clockwise direction, whereupon the heads 46 of the pins 45 pass through the openings 43. By use of the handle, the holder 33 may be held so as to face the tube 54 toward any part of the body desired to be treated, and the holder 33 may be readily moved from place to place so that irradiation of the entire surface of the body may be accomplished in a short time, or the irradiation may be maintained longer at one portion of the body than at another, in accordance with the needs of the patient. As shown in Figs. 1, 3, and 4, I provide a connector 80 by which the device may be connected to a source of alternating current through use of a flexible cord 81 and also a connector 82 through which the conductors 66 and 67 of the cable 64 may be connected with the secondary 83 of a transformer 84 which is preferably mounted within the case 10 and on the back of the supporting wall 12 so that when the supporting wall 12 is removed from the case, all of the parts of the operating mechanism, including the transformer, will be removed as a unit. On the supporting wall or instrument panel 12 I mount a current meter 85 which is in series with the secondary 83 of the transformer 84, this meter showing the current flow through the circuit including the cold quartz tube 54. On the panel 12 two time control switches 86 and 87 are mounted, the switch 86 being graduated in seconds and the switch 87 being graduated in minutes. The switch 86 is connected so that it will operate only the transformer 84 and is used for determining the period of time the cold quartz

tube 54 will be energized to give an irradiation treatment. The exposure to irradiation from this cold quartz tube is measured in seconds owing to the intensity of the ultra-violet rays which are emitted therefrom. The switch 87 connects both the transformer and the motor 26 into the electrical supply circuit and is used during the time the device is being employed for the manufacture of ozonized air.

From one contact 88 of the connector 80 a conductor 89 extends to a contact 91 of the switch 86. This conductor 89 has a fuse 92 therein and is also connected with a contact 94 of the switch 87 through a wire 93 having a switch 90 therein. When the switch 86 is actuated, the contact 91 may be brought into engagement with a contact 95 for a selected number of seconds. This contact 95 connects through a wire 96 with one side of the primary winding 97 of the transformer 84, the opposite side of which winding 97 is connected to a conductor 98 which leads to the second contact 99 of the connector 80. A pilot lamp 100 is connected in a circuit member 101 which leads from the conductor 96 to the conductor 98, thereby placing the lamp 100 in parallel with the transformer winding 97. This lamp will be illuminated during the time the switch 86 closes the circuit to the transformer winding 97. The switch 87 has a pair of contacts 102 and 103 adapted to be engaged by the contact 94. The contact 102 is connected through a wire 104 with the transformer winding 97 and the conductor 96. The contact 103 is connected to a wire 105 which in turn connects to a wire 106 extending to one side of the motor 26 which has its opposite side connected to the return wire 98. A pilot lamp 107 is connected between the conductor 105 and the conductor 98 by use of circuit means 108, so that the lamp 107 will be illuminated whenever the switch member 87 is actuated so as to cause engagement of the contact 94 with the contacts 102 and 103. It will be perceived that by use of the electrical connection shown in Fig. 4, the switch 86 will connect only the transformer winding 97 and the lamp 100 in the 110-V. supply circuit, and that the actuation of the switch 87 will connect the transformer winding 97, the motor 26, and the lamp 107 in the supply circuit.

An especial feature of my invention is the provision of means for preventing operation, through use of the minute switch 87, of the ultra-violet ray emission means when the holder 33 is removed from the position in which it is shown in Figs. 1 and 2. It is likewise a feature of the invention to provide a means for limiting the period of time the ultra-violet ray emission means may be turned on during the time the holder 33 is removed from the plate 17 for the purpose of body irradiation. The second switch 86 can be set for a period no longer than thirty seconds, for example, and during the time the holder 33 is removed from the plate 17, this second switch 86 is the only one through which the energization of the cold quartz tube 54 can be accomplished. A thirty second irradiation may produce a condition like sunburn but will not produce a severe flesh burn. As shown in Fig. 8, the flange 41 of the holder 33 has a pin 120 which projects through a vertically elongated opening 121 in the flange 42 of the plate 17 and the wall 12 into the space behind the wall 12, so that when the holder 33 is mounted on the plate 17, the switch 90 will be closed, thereby closing the circuit through the conductor 93 to the contact 94 of the minute switch 87.

This switch 90, I have shown as a spring contact 122 having a body of insulation 123 thereon adapted to be engaged by the pin 120 so as to force the spring contact 122 into engagement 5 with a second spring contact 124 when the holder 33 is mounted on the plate 17. These contacts 122 and 124 of the switch 90 are connected to the respective parts of the conductor 93. Whenever the holder 33 is removed from the plate 17, 10 the removal of the pin 120 from the position in which it is shown in Fig. 8 will permit the contact 122 to move into a position of disengagement relative to the contact 124, thereby breaking the circuit leading through the conductor 93 to the minute control switch 87. Therefore, the 15 minute switch can be employed for the purpose of energizing the cold quartz tube 54 only when the holder 33 is in a position to form the ozonization chamber 52 and in such position that no rays 20 therefrom will be emitted to the exterior. There is little possibility of a person inadvertently giving too long a treatment by irradiation, such as would occur were the minute switch inadvertently employed instead of the second switch 86 for 25 energization of the tube 54 during the time the holder 33 and its supported tube 54 are removed from the plate 17.

With relation to Figs. 1, 2, and 3, I have shown the simple manner in which I cause the air which 30 is to be ozonized to move radially through the ozonization chamber 52. For example, the air under pressure is delivered from the fan chamber 21 through a plurality of peripherally disposed holes into the chamber 52, wherein it 35 moves radially inwardly from all directions across the front and back portions of the cold quartz tube 54 to the central opening 62 of the plate 50. In Figs. 6 and 7 I show another means whereby the air to be irradiated may be caused to travel in close proximity to the surface of the cold 40 quartz tube. In this construction the wall 50 of the holder 33 is provided with a spiral rib 110 projecting so as to form a spiral channel 111 leading outwardly from the central opening 62 of the plate 50. The spiral cold quartz tube 54 is mounted in this spiral channel 111, and when 45 the holder 33 is secured to the plate 17 in the manner previously described, the outwardly disposed edge 113a of the spiral rib 110 will be engaged by the plate 17, and the plate 17 will 50 thus serve as a means for closing the spiral channel 111 so that the tube 54 will now lie in a spiral passage or conduit leading from a peripheral part of the irradiation chamber 52 to the 55 discharge opening 62. The air delivered by the fan into the irradiation chamber 52 must in this construction follow the spiral passage to the outlet 62, and in so doing the air travels along the tube 54 in such close proximity to the surface 60 thereof as to accomplish a very effective ozonization of the air.

A further feature of the invention is to provide a means whereby the switch 87 is connected with the conductor 89 only when the holder 33 65 is connected to the plate 17, and whereby the switch 86 will be connected to the conductor 89 only when the holder 33 is removed from the plate 17. To accomplish this, I make the change 70 shown in the fragmental diagram, Fig. 9, wherein the conductor 88 is led to a moving contact 130 forming a part of a switch 131 having a spring contact 132 connected through a wire 89a with the contact 91 of the switch 86, and a spring contact 133 connected through the wire 93 with the 75 contact 94 of the switch 87. As shown in Fig. 9,

the contact 130 is normally in engagement with the contact 132 when the holder 33 is removed from the plate 17, and at this time is not in contact with the contact 133, so that the switch 86 is connected with the current feed buss or connector 89 and the switch 87 is not. When the holder 33 is connected to the wall 17, the contact 130 is moved from engagement with the contact 132 into engagement with the contact 133, thereby disconnecting the switch 86 from the feed conductor 89 and connecting the switch 87 with the conductor 89. This actuation of the switch 131 may be accomplished by means forming a part of the holder 33, for example, the previously mentioned pin 120 which is indicated in Fig. 9 in 15 spaced relation to the contact 130. As the holder 33 is moved into its position of connection with the wall 17, it will engage the contact 130 and move it leftwardly from the position in which it is shown in Fig. 9 into engagement with the contact 133, at which time it will be disengaged from the contact 132.

I also provide means for varying the strength of ozone delivered through the delivery means which includes the tube 74 and the cup member 75. Such control means I prefer to make in the form of the valve plate 29, which as shown in Fig. 3 is mounted on a pivot pin 135 disposed at an edge of the air inlet opening 28 of the fan chamber 21, so that such valve plate 29 may be swung from 30 the dotted line position 136 thereof to a closed position relative to the opening 28. A control knob 137 is mounted on the supporting wall 12, preferably in a position below the time switches 86 and 87. This control knob is connected to a 35 crank 138 which is in turn connected through a link 139 with a pivot pin 141 carried by the plate 29. By rotation of the knob 137, motion may be transmitted through the link 139 to swing the plate 29 so as to vary the quantity of air which 40 may be drawn in by the fan 22 and forced through the irradiation chamber 52. If the amount of ozone delivered through the tube 74 is 45 too strong for the patient, the valve plate 29 may be moved toward closed position. If the flow of 50 ozonized air from the tube 74 into the cup 75 is less than the quantity of air breathed inwardly by the patient, air from the exterior will enter through the breather openings 76 to intermix with the ozonized air, thereby reducing the concentration of ozone in the air breathed through 55 the respiratory passages of the patient.

Although I have herein shown and described my invention in simple and practical form, it is recognized that certain parts or elements thereof 60 are representative of other parts, elements, or mechanisms which may be used in substantially the same manner to accomplish substantially the same results; therefore, it is to be understood that the invention is not to be limited to the details disclosed herein but is to be accorded the full scope of the following claims.

I claim as my invention:

1. A combined convertible ozonizer and irradiator of the character described, including: an ultra-violet ray emission means; walls forming an irradiation chamber enclosing said ray emission means, said chamber comprising cooperating parts formed so as to be moved from a position in which said chamber will be closed so as to contain air to be ozonized to a position in which said chamber will be opened so as to permit rays from said ray emission means to pass to the body to be treated; means for passing air through said irradiation chamber so that it will pass in such 75

close proximity to said ray emission means as to be ozonized by rays from said ray emission means; and means for operating said means for passing air through said irradiation chamber and 5 for actuating said ray emission means.

2. A combined convertible ozonizer and irradiator of the character described, including: an ultra-violet ray emission means; walls forming an irradiation chamber and enclosing said ray 10 emission means, said chamber comprising cooperating parts formed so as to be moved from a position in which said chamber will be closed so as to contain air to be ozonized to a position in which said chamber will be opened so as to permit rays from said ray emission means to pass to the body to be treated; means for passing air through said irradiation chamber so that it will pass in such close proximity to said ray emission means as to be ozonized by rays from said ray 15 emission means; means for operating said means for passing air through said irradiation chamber and operating said ray emission means simultaneously, or said ray emission means singly.

3. A combined ozonizer and irradiator of the 20 character described, including: an ultra-violet ray emission means; walls forming an irradiation chamber enclosing said ray emission means, said chamber being adapted to be kept closed so as to contain air to be ozonized or to be opened so as to permit rays from said ray emission means to pass to the body of a person; means for passing air through said irradiation chamber so that it will pass in such close proximity to said ray emission means as to be ozonized by rays from said 25 ray emission means; means for operating said means for passing air through said irradiation chamber and operating said ray emission means simultaneously, said operating means comprising a timing device graduated to minutes; and means 30 for actuating said ray emission means singly, said actuating means comprising a timing device graduated to seconds.

4. A combined ozonizer and irradiator of the character described, including: an electrically 35 energized ultra-violet ray emission means; walls forming an irradiation chamber enclosing said ray emission means, said chamber being adapted to be kept closed so as to contain air to be ozonized or to be opened so as to permit rays from said ray emission means to pass to the body of a person; electrically operated means for passing air through said irradiation chamber so that it will pass in such close proximity to said ray emission means as to be ozonized by rays from said 40 ray emission means; a source of electrical energy; a time switch graduated to minutes operative to connect said ray emission means and said means for passing air through said irradiation chamber to said source of electrical energy; and a time switch graduated to seconds operative to connect said ray emission means to said source of electrical energy.

5. A combined ozonizer and irradiator of the character described, including: an electrically 45 energized ultra-violet ray emission means; walls forming an irradiation chamber enclosing said ray emission means, said chamber being adapted to be kept closed so as to contain air to be ozonized or to be opened so as to permit rays from said ray emission means to pass to the body of a person; electrically operated means for passing air through said irradiation chamber so that it will pass in such close proximity to said ray emission means as to be ozonized by rays from said ray 50 emission means; a source of electrical energy; a time switch graduated to minutes operative to connect said ray emission means and said means for passing air through said irradiation chamber to said source of electrical energy; and a time switch graduated to seconds operative to connect said ray emission means to said source of electrical energy.

source of electrical energy; a time switch graduated to minutes operative to connect said ray emission means and said means for passing air through said irradiation chamber to said source of electrical energy; a time switch graduated to 5 seconds operative to connect said ray emission means to said source of electrical energy; and means for preventing energization of said ray emission means through use of said switch graduated to minutes, during the 10 time said chamber is open for irradiation of the body.

6. A combined ozonizer and irradiator of the character described, including: an ultra-violet ray emission means; walls forming an irradiation 15 chamber enclosing said ray emission means, said chamber being adapted to be kept closed so as to contain air to be ozonized or to be opened so as to permit rays from said ray emission means to pass to the body of a person; means for passing 20 air through said irradiation chamber so that it will pass in such close proximity to said ray emission means as to be ozonized by rays from said ray emission means; means for operating said means for passing air through said irradiation chamber and operating said ray emission means simultaneously, said operating means comprising a timing device operative to maintain the period of operation of said operating means over a relatively long time; and means for actuating said ray 25 emission means singly, said actuating means comprising a timing device operative to maintain the period of operation of said actuating means over a relatively short time limited so that at any single operation of said actuating means the body 30 irradiation thereby accomplished can be for no greater than a prescribed length of time.

7. A combined ozonizer and irradiator of the character described, including: a supporting wall; securing means associated with said supporting wall; a holder detachably connected to said supporting wall by said securing means; said wall and said holder forming an irradiation chamber in conjunction with said supporting wall; a ray emission tube secured to said holder 40 in such position that it will lie in said chamber when said holder is connected to said wall, said holder being of such character that when it is detached from said wall it may be caused to face a body portion for which irradiation is desired; means for forcing air through said chamber so that it may be irradiated by emanations from said ray emission tube; and flexible means connecting said ray emission tube to a source of electrical energy whereby said tube may be energized 45 so as to give off rays.

8. A combined ozonizer and irradiator of the character described, including: a supporting wall; securing means associated with said supporting wall; a holder detachably connected to said supporting wall by said securing means, said wall and said holder forming an irradiation chamber; a ray emission tube secured to said holder in such position that it will lie in said 60 chamber when said holder is connected to said wall, said holder being of such character that when it is detached from said wall it may be caused to face a body portion for which irradiation is desired; means for forcing air through said chamber so that it may be irradiated by emanations from said ray emission tube; a transformer connected to said supporting wall; means for connecting the primary of said transformer to a source of electrical current supply; and 65

flexible conductors connecting the secondary of said transformer to said ray emission tube.

9. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; and means for connecting said ray emission tube to a source of electrical energy whereby said tube may be energized so as to give off rays.

10. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; long period timing means operative to control the period of energization of said tube when said holder is connected to said supporting wall; short period timing means operative to control the period of energization of said tube when said holder is disconnected from said wall.

11. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced

through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; an impregnating means connectable to said outlet means, said impregnating means having a discharge fitting at the rearward end thereof; and a breather attachment having means for connecting it to said discharge fitting of said impregnating means or to said outlet means of said holder.

12. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; long period timing means operative to control the period of energization of said tube when said holder is connected to said supporting wall; short period timing means operative to control the period of energization of said tube when said holder is disconnected from said wall; an impregnating means connectable to said outlet means, said impregnating means having a discharge fitting at the rearward end thereof; and a breather attachment having means for connecting it to said discharge fitting of said impregnating means or to said outlet means of said holder.

13. A combined ozonizer and irradiator of the character described, including: a supporting wall; securing means associated with said supporting wall; a holder detachably connected to said supporting wall by said securing means, said holder having a plate disposed close to said supporting wall so as to form a relatively shallow chamber; a ray emission tube secured to the inner face of said plate so as to lie in said chamber when said holder is connected to said wall, said holder being of such character that when it is detached from said wall it may be caused to face a body portion for which irradiation is desired; means for forcing air through said chamber so that it may be irradiated by emanations from said ray emission tube; and flexible means connecting said ray emission tube to a source of electrical energy whereby said tube may be energized so as to give off rays.

14. A combined ozonizer and irradiator of the character described, including: a supporting wall; securing means associated with said supporting wall; a holder detachably connected to said supporting wall by said securing means, said holder

having a plate disposed close to said supporting wall so as to form a relatively shallow chamber, there being an air inlet opening through said wall and leading into said chamber; a fan connected to said inlet opening so as to force air into said chamber; a ray emission tube secured to the inner face of said plate so as to lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; long period timing means operative to control the period of energization of said tube when said holder is connected to said supporting wall; short period timing means operative to control the period of energization of said tube when said holder is disconnected from said wall; an impregnating means connectable to said outlet means, said impregnating means having a discharge fitting at the rearward end thereof; and a breather attachment having means for connecting it to said discharge fitting of said impregnating means or to said outlet means of said holder.

15. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; an impregnating means connectable to said outlet means, said impregnating means having a discharge fitting at the rearward end thereof; and a breather attachment having means for connecting it to said discharge fitting of said impregnating means or to said outlet means of said holder.

15. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; an impregnating means connectable to said outlet means, said impregnating means having a discharge fitting at the rearward end thereof; and a breather attachment having means for connecting it to said discharge fitting of said impregnating means or to said outlet means of said holder.

16. A combined ozonizer and irradiator of the character described, including: a supporting wall; securing means associated with said supporting wall; a holder detachably connected to said supporting wall by said securing means, said wall and said holder forming an irradiation chamber, there being an air inlet opening through said wall and leading into said chamber; a fan connected to said inlet opening so as to force air into said

chamber; a ray emission tube secured to said holder in such position that it will lie in said chamber when said holder is connected to said wall, said holder being of such character that when it is detached from said wall it may be caused to face a body portion for which irradiation is desired; means for operating said fan so that air will be forced through said chamber so that it may be irradiated by emanations from said ray emission tube; outlet means carried by said holder, said outlet means forming a discharge passage leading from said irradiation chamber; means for connecting said ray emission tube to a source of electrical energy whereby said tube may be energized so as to give off rays; an impregnating means connectable to said outlet means, said impregnating means having a discharge fitting at the rearward end thereof; and a breather attachment having means for connecting it to said discharge fitting of said impregnating means or to said outlet means of said holder, said breather including a cup adapted to engage a body orifice member, there being an air orifice provided by said cup communicating with the exterior; and means for varying the flow of air through said irradiation chamber.

17. An ozonizer of the character described, including: a cold quartz violet ray emission tube; walls separably connected so as to be moved from a position in which said chamber is closed so as to contain air to be ozonized to a position in which said chamber is open so that rays from said tube may pass to a body to be treated; means for passing a flow of air to be ozonized through said chamber, there being walls in said chamber disposed so as to deliver air of said flow within four millimeters of said tube; delivery means from which the ozonized air may be breathed by a person, there being means associated with said delivery means providing an orifice connecting the interior thereof with the exterior atmosphere; and means for varying the flow of air through said irradiation chamber and said delivery means.

18. A combined ozonizer and irradiator of the character described, including: an ultra-violet ray emission means; walls forming an irradiation chamber enclosing said ray emission means, said chamber being adapted to be kept closed so as to contain air to be ozonized or to be opened so as to permit rays from said ray emission means to pass to the body of a person; means for passing air through said irradiation chamber so that it will pass in such close proximity to said ray emission means as to be ozonized by rays from said ray emission means; means for operating said means for passing air through said irradiation chamber and operating said ray emission means simultaneously; and means for actuating said ray emission means singly, said actuating means comprising a timing device operative to maintain the period of operation of said actuating means over a relatively short time limited so that at any single operation of said actuating means the body irradiation thereby accomplished can be for no greater than a prescribed length of time.

19. A combined ozonizer and irradiator of the character described, including: an electrically energized ultra-violet ray emission means; walls forming an irradiation chamber enclosing said ray emission means, said chamber being adapted to be kept closed so as to contain air to be ozonized or to be opened so as to permit rays from said ray emission means to pass to the body of a person; electrically operated means for passing air

- through said irradiation chamber so that it will pass in such close proximity to said ray emission means as to be ozonized by rays from said ray emission means; a source of electrical energy; a
- 5 5 dual effect switch means operative to connect said ray emission means and said means for passing air through said irradiation chamber to said source of electrical energy; a time switch graduated to seconds operative to connect said ray
- 10 10 emission means to said source of electrical energy; and means for preventing energization of said ray emission means through use of said dual effect switch means, during the time said chamber is open for irradiation of the body.
- 15 15 20. A combined ozonizer and irradiator of the character described, including: a stationary member and a movable member formed so as to enclose an irradiation chamber and so that said movable member may be moved from closed to
- 20 20 open position relative to said stationary member; ultra-violet ray emission means secured to said movable member in such position that it will lie in said chamber when said members are in closed relation; a source of energy for said ray emission means; and means for connecting said ray emission means to said source of energy when said movable member is in both open and closed relation to said stationary member.
21. An ozonizer of the character described, including: a pair of detachably connected walls forming an irradiation chamber when in closed relation, one of said walls having a continuous groove in the inner face thereof; an ultra-violet ray emission tube; and means for producing a flow of air along said groove from end to end thereof and along the ray emission tube therein.
22. In a device of the character described, the combination of: a primary wall and a secondary wall detachably connected and forming an irradiation chamber when connected; a ray emission means in said chamber; a source of energy for said ray emission means; conductors forming a circuit connecting said source of energy with said ray emission means; a switch in said circuit normally open when said walls are disconnected; and means operating in response to the connecting together of said walls to close said switch.

ALBERT L. MILLER.
